UNITED STATES PATENT OFFICE

163,689

BUILDING PANEL

Erich Gach, Chicago, Ill., assignor to Bird & Son, inc., East Walpole, Mass., a corporation of Massachusetts

Continuation of design application Serial No. 141,137, August 30, 1947. This application December 1, 1949, Serial No. 6,370

Term of patent 14 years

(Cl. D68—1)

To all whom it may concern:

Be it known that I, Erich Gach, a citizen of the United States, residing at Chicago, in the county of Cook and State of Illinois, have invented a new, original, and ornamental Design for Building Panel, of which the following is a specification, reference being had to the accompanying drawing, forming a part hereof wherein

Fig. 1 is a front view of a building panel, showing my new design;

Fig. 2 is a section on line 2—2 of Fig. 1 illustrating my design;

Fig. 3 is a section on line 3—3 of Fig. 1 further illustrating the design; and

Fig. 4 is a three-quarter perspective of the building panel further illustrating my design.

This application was filed as a continuation of Serial No. D. 141,137, filed by applicant August 30, 1947, abandoned January 31, 1950.

I claim:

The ornamental design for a building panel, as shown.

ERICH GACH.
